UNITED STATES PATENT OFFICE.

ACHILLES COLLOWAY GOUGH, OF POCATELLO, IDAHO.

FAN.

Application filed October 21, 1921. Serial No. 509,404.

To all whom it may concern:

Be it known that I, ACHILLES C. GOUGH, a citizen of the United States, residing at Pocatello, in the county of Bannock and State of Idaho, have invented certain new and useful Improvements in Fans; and I do hereby declare the following to be a full, clear, and exact description of the invention, such as will enable others skilled in the art to which it appertains to make and use the same.

This invention relates to an improvement in fan structure and more particularly to fans for use in connection with automobile engines for cooling the same.

The object of the present invention is to provide a fan which will operate similarly to those now in common use to create a movement of air through the radiator and to direct the draft of cooling air over the exterior of the engine casing and which will at the same time operate to divert, propel and cleanse from impurities such as dust and grit, a portion of air and supply the same for use in the carburetor or interior of the engine casing where desired.

The invention consists in the novel construction, arrangement and combination of parts hereinafter more particularly described and claimed.

One sheet of drawings accompanies this specification, as part thereof, in which like reference characters indicate similar parts throughout.

Fig. 1 is a fragmentary side elevation of an automobile engine showing my improved fan in position;

Fig. 2 is a plan view of my improved fan;

Fig. 3 is a transverse sectional view taken on the line 3—3 of Fig. 2;

Fig. 4 is a diagrammatic illustration of a method for laying out my improved fan.

In accordance with my present invention, fan blades 1 are made hollow, each having one face 4 inclined at an angle with the axis of rotation of the fan and provided with a plurality of radially extending slits 5, lips 6 adjacent each of said slits 5 being set at an angle so as to present faces opposed to the direction of rotation of the fan, as illustrated in Fig. 3, the direction of rotation being indicated in that Figure by the arrow Y.

The front edge 7 of each blade may be made straight but the back edge 8 of each blade is made to conform to a modified involute curve extending from a substantially large radius adjacent the front edge 7, as at 9, and concluded at a relatively short radius adjacent the front edge 7 of the opposite fan, as at 10. By this structure, it will be apparent that the back edge 8 of each blade will operate with a cam like effect upon all air entering the fan blade through the slits 5 directing said air generally as indicated by the arrow Z (Fig. 2) toward the center of the fan 11.

The fan is mounted upon a hollow shaft 12 which is provided with suitable orifices (not shown) communicating with the interior of the fan blades so that air directed toward the center of the fan will be forced through hollow shaft 12 which may be connected by a suitable tube 2 to a heater B and thence through suitable tubes 3—3 to the carburetor C and the breather D.

In operation it will be apparent that upon rotation the fan thus directed will blow a cooling blast upon the engine A, while at the same time a certain amount of air will be forced in through the openings 5 and propelled by the cam surfaces 8 through the hollow shaft 12, as indicated. The air thus taken into the fan structure will be cleaned through the operation of the deflecting lips 6 which will operate to expel any particles of grit or dust coming in contact therewith.

The curve for the back of the fan blades may be easily computed as for an involute curve with slight modifications at each end to make the curve smooth in connection with the opposing blade. Referring to Fig. 4, the curve 8 is laid off so that the angle X, between the perpendicular to any particular radius and the tangent to the curve intersecting said radius at that point, increases gradually and the least possible amount as the radius R decreases. In general any curve drawn to proportionally diminishing radii will, it is believed, prove effective, at least to some degree.

Modifications in the exact curve and the precise arrangement and construction of the parts will readily suggest themselves to those skilled in the art, but within the scope of the present invention.

Having thus described my invention, I claim:

1. A fan having hollow blades, the rear faces of said blades curved from a maximum radius adjacent the front edge of the blade to a minimum radius adjacent the front edge of an adjoining blade, the advancing faces of said blades being provided with a plurality of radially extending slits.
- 10 2. An improved fan having hollow blades set at an inclination to the axis of rotation, means for admitting air into said blades through the advancing faces thereof, the back walls of said blades being curved to

I provide a cam like surface to force the 15 air received into said blades toward the center of the fan.

3. In an air cleaning and propelling device, a hollow blade having an advancing face set at an inclination to the axis of rotation, means in said advancing face to admit air to the interior of said blade, the back wall of said blade conforming to a substantially involute curve, as and for the purposes specified. 20

In testimony whereof I affix my signature. 25

ACHILLES COLLOWAY GOUGH.
